UNITED STATES PATENT OFFICE

FRED FRAY, OF PADUCAH, KENTUCKY, ASSIGNOR TO UNDERWOOD ELLIOTT FISHER COMPANY, OF NEW YORK, N. Y., A CORPORATION OF DELAWARE

TYPEWRITING MACHINE

Application filed December 20, 1927. Serial No. 241,310.

This invention relates to line-spacing levers, particularly for use on Underwood portable typewriting machines, and the object of the invention is to improve such levers to secure increased convenience and ease of operation for the typist.

A typewriting machine of this type includes a carrying case, and it is desirable to keep the weight of the machine and case as low as possible, and the dimensions, particularly the height, as small as possible. In order to keep the height of the carrying case low, the machine has been provided with an integral horizontally-extending line-space lever and finger-piece mounted on the platen-carriage with just sufficient clearance to actuate the line-space mechanism and effect the return of the platen without interfering with any of the operating parts of the machine. The lever and finger-piece do not extend above the highest points of the typewriter-parts and therefore the height of the portable case is not increased to accommodate the lever.

According to the present invention the line-space-lever is provided with a finger-piece pivoted thereto, which does not increase the weight of the machine, and, in its lowermost position, will not interfere in any manner with the machine being positioned in a carrying case of the same height as before. When the typewriter is in use this pivoted finger-piece may be swung so as to extend upwardly for the convenience of those accustomed to an upwardly-extending finger-piece, to facilitate in the operation of the machine.

The finger-piece is provided with spring-operated means for yieldingly securing it in its upwardly-extending position for operating the shift-lever. The lever has a stop for supporting the finger-piece in its lowered horizontal position, so that it will not fall below the limit provided by the stop and interfere with any of the typewriter-parts. In said horizontal position it may also be engaged for operating the carriage-return and line-spacing of the platen by those who may prefer to operate it in that position in the same manner as with the prior form of line-

space lever provided on the portable machines.

This feature is of great value when the machine is used by a child, as the finger-piece in the horizontal position is considerably lower and can be more easily reached than when it is vertical.

The finger-piece in the horizontal position extends outward from the end of the lever an appreciable distance and thereby increases the leverage, thus greatly facilitating the operation of moving the carriage.

These features permit the machine to be operated by children and others with the least expenditure of energy.

In practice the finger-piece may not be raised at all, but left permanently in its horizontal or extended position. For this reason no spring is provided to automatically raise the finger-piece when the cover is removed from the carrying case.

Other features and advantages will hereinafter appear.

In the accompanying drawings,

Figure 1 is a cross-sectional view, in elevation, showing a portion of an Underwood portable typewriter with a line-space lever having a finger-piece, in accordance with the present invention, applied thereto.

Figure 2 is an elevational detail view of the finger-piece for the line-space-lever, in accordance with this invention.

Figure 3 is a plan view of a portion of the typewriter with the present invention applied thereto.

Figure 4 is a perspective view, showing the finger-piece in its upwardly-extending operative position.

Figure 5 is a perspective view of the line-space-lever, with the parts of the improved finger-piece in disassembled relation.

Referring to the drawings, the present invention is disclosed as applied to an Underwood four-bank portable typewriting machine, only such parts of the machine being illustrated as are essential to illustrate the application of the present invention.

The machine shown includes a frame 10 provided at the rear portion thereof with a carriage 11, which is reciprocably mounted 100

thereon by means of rails 12 and 13, which co-operate with ball-bearings 15. The carriage is positioned in said frame as low as possible with its upper portion extending 5 above the other parts of the machine, the highest of which is the rear paper-table 16, which determines the position of the top 17 of the portable case 18.

In order to return the carriage 11 to line- 10 starting position and at the same time to line-space the platen 19, which is rotatably mounted by means of a platen-shaft 20 in the carriage, the machine is provided with a rocking lever 21 having an arm 22 for actuating the 15 line-spacing mechanism, and a forwardly-extending arm 23 for operating it. Lever 21 is pivotally mounted on a vertical stud 24, and the arm 22 is connected by means of an intervening pawl 25 to a line-space ratchet 26 carried on the platen-shaft 20. The pawl is loosely connected with the lever-arm 22 by means of a stud 27, and is slidingly mounted, in a slot 28, by means of a shouldered screw 29.

25. In accordance with this invention, the forward arm 23 of the lever 21 is operated by means of a finger-piece 30 pivotally mounted upon a suitable tongue 23a formed on the outer end thereof, by means of a pivot-pin 31.

30. Being pivotally mounted on the lever-arm, the finger-piece may be positioned horizontally, so as not to engage the carrying case or extend above the uppermost portion of the lever-arm, when the typewriting machine is 35 enclosed in its carrying case.

When it is desired to operate the machine, the finger-piece may be swung to an upright position where it will be releasably held by means of a plunger follower or detent 32 positioned in a hole 33 in the finger-piece and forced outwardly by means of a spring 34 with sufficient pressure to ride into a recess or notch 36 in the tongue 23a of the lever-arm 23 and yieldingly maintain the finger-piece in its upright position. The plunger 32 is provided with a tang 35 on its inner end around which the spring 34 engages, whereby the spring and plunger will be freely guided in the hole 33.

50. When it is desired to turn the finger-piece downwardly, it may be forced sufficiently to cause the plunger to ride out of the recess 36, and then ride over a dwell-face 23b to its lowermost position where a notch 37 thereof 55 will engage a projecting stop 38 on the end of the tongue of the lever-arm 23 to hold it in a horizontal position. Stop 38 prevents the finger-piece from dropping to a position where it can engage any of the typewriter-parts, as, for example, the spool-cup 39, in the event that the carriage is unintentionally moved, or that it is desired to operate the typewriter with the finger-piece in its horizontal position. In the horizontal position 60 of the finger-piece the spring 34 operating

upon the plunger 32 offers a frictional resistance for maintaining the finger-piece in its lowered position.

Variations may be resorted to within the scope of the invention, and portions of the 70 improvements may be used without others.

Having thus described my invention, I claim:

1. In a machine of the character described, the combination with a pivoted operating 75 lever, of a cam-surface formed at the free end of the lever, an adjustable finger-piece curved at one end to form a concave finger-grip and slotted at the other end to receive the lever, means for assembling the finger-grip to the lever, and a detent, included in the finger-grip, effective for engaging the cam-end of the lever and retaining the finger-piece in adjusted position.

2. In a machine of the character described, 80 the combination with a pivoted operating lever, of a cam-surface at the free end, including a longitudinally projecting stop, an adjustable finger-piece curved at one end to form a concave finger-grip and slotted at 85 the other end to receive the lever, a stop-surface in said slot and effective to engage said stop, a pivot for assembling the finger-grip to the lever, and a detent, included in the finger-piece, effective for engaging the cam-surface of the lever and retaining the finger-piece in adjusted position.

FRED. FRAY.
